UNITED STATES PATENT OFFICE.

MARY E. PHOEBUS AND MARGARET NATALIE PHOEBUS, OF TOMS RIVER, NEW JERSEY.

DOLL AND DOLL CUT-OUT.

1,365,601.

Specification of Letters Patent. Patented Jan. 11, 1921.

Application filed February 28, 1920. Serial No. 362,025.

To all whom it may concern:

Be it known that we, MARY E. PHOEBUS and MARGARET NATALIE PHOEBUS, both citizens of the United States, residing at Toms River, in the county of Ocean and State of New Jersey, have invented certain new and useful Improvements in Dolls and Doll Cut-Outs, of which the following is a specification.

10 Our invention relates to a new combination in a doll, or animal representation or toy, and the novelty consists in the arrangement of the parts as hereinafter more fully set forth.

15 There have been many attempts to make the representation of an animal or other figure on a card, or in a doll or toy, appear to have some light or activity in the eyes, as such an effect makes the figure represent-
20 ed so very much more attractive in the eyes of those who are looking at the same.

All of these attempts have resulted in a device which is too complicated and too expensive to be useful for the purposes de-
25 sired, and our device has overcome this difficulty, obtaining the desired effect of actual life in the eyes of the figure or doll by means of a device which is most simple and inexpensive.

30 In the drawings Figure 1 is a perspective of a card embodying our invention. Fig. 2 is a cross-section of a portion of Fig. 1 on the line 2—2. Fig. 3 is a perspective of

the upper portion of the back of the card, the lower portion being broken away, and 35 also a portion of the retaining member being broken away, in order to show the manner in which the device is secured to the card in order to obtain the desired effect.

Referring to the drawings 4 is a figure of 40 a cat which is printed or otherwise disclosed on a card 5, which has eye openings 6 cut therein.

A mirror 7 is rigidly secured to the back of the card 5 by means of a retaining mem- 45 ber 8, so that the mirror 7 entirely covers the two eye openings 6. Two mirrors may be used instead of one, and this undoubtedly proves of great advantage in some instances. The lower portion of the card 5 designated 50 as 9 is adapted to be used for the usual advertising purposes.

The device as shown in the drawings is merely illustrative of the use of our invention, which is also adapted to be used with 55 dolls or toys or other representations of animals or people which have eye openings.

We claim:

In combination with a figure having eye holes and mirrors so mounted on said figure 60 back of said holes as to show their reflecting surfaces therethrough.

In testimony whereof we affix our signatures.

MARY E. PHOEBUS.

MARGARET NATALIE PHOEBUS.
